UNITED STATES PATENT OFFICE.

YAICHIRO SHIBA, OF SAN JOSE, CALIFORNIA.

AUTOMOBILE SIGNAL.

1,426,610.

Specification of Letters Patent. Patented Aug. 22, 1922.

Application filed February 24, 1920. Serial No. 360,949.

To all whom it may concern:

Be it known that I, YAICHIRO SHIBA, a subject of Japan, residing in San Jose, county of Santa Clara, State of California, have invented certain new and useful Improvements in Automobile Signals, whereof the following is a specification.

This invention relates to automobile signals, to indicate when the machine is about 10 to stop, or which way it is about to turn.

To such ends the invention comprises an arm which may be projected outward from the machine, either straight out, or at an angle, its position, when so projected, giving 15 the intended signal. The invention includes mechanism by which the arm may be operated, to the above ends. The invention includes also a series of lights in a line, preferably on the arm, which give a position signal at night.

I have fully illustrated my invention in the accompanying two sheets of drawing, in which I have shown a mechanism containing it, and in which

25 Figure 1 is an elevation of the mechanism, as seen by the driver of the machine to which it is applied, and shows the signal arm projected at right angles, with its position when entirely retracted indicated in 30 dotted lines.

Figure 2 is a top view of the same.

Figure 3 is a partial sectional elevation, the section being taken on the line *a*, *a*, of Figure 1 looking in the direction of the 35 arrows.

Figure 4 is a section on the line *b*, *b*, of Figure 3 looking in the direction of the arrows.

Figure 5 is a section, on a larger scale, on 40 the line *c*, *c*, of Figure 2 looking in the direction of the arrows.

In the figures:—The apparatus is shown as attached to rail of the windshield of an automobile, 1 being the side rail portion and 45 2 the glass portion. To the side rail portion, 1 is attached an upright bar 3, by means of clamps 4, which may be fastened by a thumb nut and bolt 5. A bracket 6 is supported by the bar 3, and is made rigid 50 therewith in any convenient manner, as by notches 7 engaging teats 8 on the clamps 4. An arm 9 is pivotally connected to the bracket 6 so that it may hang downward against the face of the bracket, as appears 55 on dotted lines in Figure 1, or may be swung

upward and outward as shown in full lines in that figure.

The mechanism for operating arm 9 is as follows:—A plate 10 projects backward from the upper part of bracket 6, and has a circular edge 11, with notches 12 and 12^a therein. At the center of the circle forming the edge 11 is an arbor 13, which, on one side of the plate 10 carries a pinion 14, and, on the other side, a crank 15, with a handle 16. 60 A pinion 17 attached to arm 9, enmeshed with pinions 14, whereby a movement of crank 15, determines a swing of arm 9. A combined housing and bearing plate 18 is secured to plate 10, and serves to cover pinion 14 and provide a bearing for the arbor 19 upon which arm 9 and pinion 17 oscillate. The crank 15 is provided with a projection 20 and lip 21, embracing the edge of plate 10. A dog 22, pushed outward by a spring 70 23, housed in a hole in the projection 20, engages the notches 12 and 12^a, and holds arm 9 in the position corresponding thereto.

In practice, arm 9 normally hangs down, as shown in the dotted lines of Figure 1. 80 When it is desired to give a signal, crank 15 is operated, and, through pinions 14 and 17, swings arm 9 outward into one of the three positions indicated by the three notches 12. The particular signal given will be fixed by 85 the rules of the road. For example; straight out as shown in Figure 1 may mean "Left" which may be indicated by the letter "L" stamped upon the circular edge 11 as shown in Figure 3 out with a downward inclination 90 may mean "Stop" indicated by the letter "S" stamped upon the circular edge 11, and out with an upward inclination may mean "Right" indicated by the letter "R" also stamped upon the circular edge 11, and the notch 12^a, is for the purpose of holding the arm 9 out of operative position as shown in dotted lines Figure 1 and stop pin 24 is to limit the movement of the crank 15.

Having thus described my invention, and 100 an embodiment of it, in the full, clear and exact terms required by law and knowing that it comprises novel, useful and valuable improvements in the art to which it pertains, I here state that I do not wish 105 to be limited to the precise construction and arrangement of the several parts, as herein set forth, as the same may be variously modified by a skilled mechanic without departing from the spirit of the invention.

What I claim and desire to secure by Letters Patent of the United States, is the following, to wit:

1. An automobile signal device, comprising, in combination, a bracket adjustably mounted upon the wind shield rail of the automobile, an arm pivotally connected to said bracket and adapted to swing upward and outward therefrom, means for operating 10 said arm, consisting of a plate projecting from said bracket, intermeshing pinions secured upon said arm and plate, a lever connected to one of said pinions adapted to move said arm, means on said lever engaging said plate and adapted to retain said arm in a predeterminate position.
2. An automobile signalling device comprising, in combination, a bracket adjustably mounted upon the wind shield rail of the 20 automobile, an arm pivotally connected to said bracket and concealed thereby when not in operation, said arm adapted to swing upward and outward from said bracket, means for operating said arm, consisting of 25 a plate projecting from said bracket, a pinion on said arm and a second pinion on said plate engaging said first pinion, a lever pivotally secured to said plate and engaging said second pinion, means on said lever 30 engaging the upper edge of said plate and adapted to retain said lever in a predeterminate position.
3. An automobile signalling device, comprising, in combination an upright bar secured to the wind shield rail of the automobile, a bracket adjustably mounted upon 35 said upright bar and supported thereby, an arm pivotally connected to said bracket and adapted to swing upward and outward therefrom, means for operating said arm, consisting 40 of a plate projecting backward from

said bracket and provided with notched edge, an arbor journally upon said plate, a pinion and a crank secured to said arbor, a pinion secured to said arm and engaging 45 said first pinion whereby a movement of the crank determines a swing of said arm, a dog on said handle adapted to engage said notched edge of the plate and retain said arm in a predeterminate position. 50

4. An automobile signalling device, comprising, in combination an upright bar adjustably secured to the wind shield rail of the automobile by means of a pair of clamps, a bracket mounted upon said upright bar between said clamps and supported thereby, means upon said clamps to hold said bracket in rigid position, an arm pivotally connected to said bracket adapted to hang downward against the face of the bracket and swing 60 upward and outward therefrom, mechanism for operating said arm, consisting of a plate projecting backward from said bracket and provided with a circular edge having notches, an arbor journally upon said plate 65 carrying on one side thereof a pinion and on the other a crank, said crank having a handle, a pinion secured to said arm and engaging said first pinion whereby a movement of the crank determines a swing of said 70 arm, a dog on said handle provided with a spring, adapted to engage said notches upon the circular edge of said plate and retain said arm in a predeterminate position. 75

In testimony that I claim the foregoing I have hereto set my hand in the presence of two witnesses, this 18th day of February 1920.

YAICHIRO SHIBA.
